UNITED STATES PATENT OFFICE.

MICHAEL R. GATELY, OF BOSTON, MASSACHUSETTS.

DESIGN FOR A BOOK-CLASP.

SPECIFICATION forming part of Design No. 13,250, dated August 22, 1882.

Application filed May 4, 1882. Term of patent 14 years.

To all whom it may concern:

Be it known that I, MICHAEL R. GATELY, of Boston, in the county of Suffolk and State of Massachusetts, have invented a new and 5 original Design for Book-Clasps, of which the following is a specification.

The nature of my design is shown in the accompanying illustration, forming a part of this specification, and representing an ordinary 10 book-clasp adapted to be hinged to one lid of a Bible or other book, and to be detachably secured to the other lid.

The design consists in a representation of the scene of the Crucifixion engraved, stamped, 15 or otherwise delineated on the outer surface of the clasp. Kneeling female figures are

placed on opposite sides of the foot of the Cross, and rays of light radiate from the Cross, as shown.

The clasp, with this design, is intended for 20 Catholic bibles and other books.

I claim—

The design for a book-clasp, substantially as shown and described.

In testimony whereof I have signed my name 25 to this specification, in the presence of two subscribing witnesses, this 2d day of May, 1882.

M. R. GATELY.
